UNITED STATES PATENT OFFICE

2,047,082

GRADUATING HAIR CLIPPER

John Russo, Boston, Mass.

Application October 8, 1932, Serial No. 636,864

4 Claims.

(Cl. 30—1)

My invention relates to improvements in graduating hair clippers and it has for its object to improve the construction and mode of operation thereof.

5 It is also an object of this invention to simplify and improve the operation of graduated hair cutting to the end that the hair may be cut expeditiously in a uniform and accurate manner.

To these ends I have provided an improved 10 hair clipper having certain novel features of construction and mode of operation set forth in the following description, the several novel features being particularly pointed out and defined in the claims at the close thereof.

15 In the accompanying drawing:

Figure 1 is a side elevation of a hair clipper constructed in accordance with this invention.

Figure 2 is a bottom plan view of the bottom plate hereinafter described showing the parts in 20 separated relationship.

Figure 3 is a front elevation of the clipper shown in Figure 1.

The embodiment of my invention herein illustrated comprises a bottom plate consisting of two 25 sections, 1 and 2, the former being provided with a rigid handle 1^a. The instrument is also provided with a complementary handle member 11 which is pivotally supported by the bottom plate section 1 and which, when vibrated, serves to 30 reciprocate a cutting comb 16, as usual.

As shown in Figure 2 the bottom plate section 2 is constructed as a comb which is held against the head of the subject.

The forward comb element or section 2 of the 35 bottom plate is provided with a pair of rearwardly extending rods 2^a which are slidably mounted within holes 1^b provided in bottom section 1. The bottom face of section 1 is flat and the rods 4 are parallel therewith. The rear end 40 portions of the holes within which the rods are mounted are threaded interiorly to receive adjustable stop screws 1^c. These stop screws may be set for engagement with the inner ends of the rods thereby to limit the extent of movement of section 2 toward the section 1. That is, the stop screws may be set so as to position section 2 relatively to cutting comb 16 when said section 2 is 45 at the limit of its inward movement.

Secured in position upon the rear section 1 of the bottom plate by means of a threaded stem 12 and wing nut 13 is a sheet metal cap 3 whose lower front end edge portion 17 bears against the top of the cutting comb 16 and holds the latter 50 against upward displacement as said comb is re-

ciprocated. The top portion of bottom section 1 consists of an intermediate cutting comb plate 14 that is a rigid part of section 1 and against the top of which the opposite side walls of the cover 3 are fitted.

5 Projecting from one of the side walls of cover 3 is a stud 3^a on which is loosely mounted a pulley 4 to which one end of a flexible cable 7 is fastened. The opposite end of cable 7 may be provided with a ring 15 for engagement with a fixture, or which 10 may be held by one hand of the user of the clipper while he employs the other hand to operate and control the latter.

One end of a link 5 is pivotally connected at 4^b to the inner face of pulley 4, while the opposite end of said link is pivotally fastened by a connector 9 to one arm of a lever 8 that is pivotally connected by a fulcrum screw 10 to the adjacent side wall of cover 3. The lever 8 may be a bail-shaped structure which embraces the cover 20 3 as shown in Fig. 3, the oppositely disposed legs or arms thereof being pivotally connected to opposite sides of cover 3 as described.

One end of a link 6 is pivotally connected at 2^c to one side of the section 2 of the bottom plate 25 while the opposite end of said link 6 is pivotally fastened by a connector 9^a to one of the arms of lever 8.

Each cutting stroke of the clipper is started with the bottom comb element or section 2 in its 30 retracted position and as the clipper is moved forward the operator restrains or holds back upon the cord or cable 7 which acts through the motion transmitting gearing including pulley 4, link 5, lever 8 and link 6 to gradually advance 35 the bottom section 2 relatively to the cutting comb 16 with the result that the cutting action is graduated so that the clipper cuts shortest at the start and is gradually adjusted away from 40 the head by section 2 as the clipper is moved forward.

I am aware that graduating clippers have heretofore been provided having a bottom plate that was manually advanced during each cutting stroke of the clipper, but it is a distinguishing feature of advantage to the above described construction that the flexible cable 7 which is manipulated by one hand of the operator, permits the latter to fully control and manipulate the instrument with his other hand without interference by the flexible cable 7, the pull upon said cable during the forward stroke of the clipper having no other appreciable effect than to advance the section 2 of the bottom plate thus leaving the instrument 55

free to be guided and moved about by the other hand of the user both laterally and back and forth.

Preferably the lever 8 is formed with a slot 8^b within which the connector device 9 is fixed with provision for adjustment lengthwise of said slot when desired. Also the connector device 9^a is preferably fixed within a slot 8^a formed in lever 8 with provision for adjustment lengthwise thereof when desired.

A series of holes 8^d formed in lever 8 provides for vertical adjustment of the latter and I may also provide the pulley 4 with a plurality of angularly spaced apart holes 4^a for reception of the pivotal connector device 4^b.

The arm of lever 8 with which the links 5 and 6 are connected is also formed with a third slot 8^c disposed above the fulcrum 10 of said arm and this slot is provided to permit of dispensing with pulley 4 and link 5 in which case the connector 9 may be transferred to the slot 8^c and the end of cable 7 connected therewith. Or, if the pulley and link are dispensed with, the end of the cable 7 may be merely tied to the lever 8 at the slot 8^c.

Of course it is possible to control the gauging section 2 of the bottom plate by direct manipulation of lever 8, but the objection thereto is that such direct manual control interferes, to a material extent, with the proper manipulation of the instrument by the other hand of the operator.

If desired the cable 7 may be made sufficiently long to permit the ring 15 to be engaged with a fixture at the rear of the barber's chair so that the clipper instrument can be carried about from one side of the chair to the other, the barber holding the cable 7 intermediate its ends while performing the cutting operations.

What I claim is:

1. A clipper of the character described con-

structed with a bottom plate consisting of a rear section and a front section, said front section being slidably associated with said rear section; a handle member rigidly connected with said rear section; a lever carried by said rear section; a pulley rotatably supported by said rear section; a link connecting said pulley and lever; a link connecting said lever with said front section, and a flexible cable having one end thereof connected with said pulley and manually operable during a cutting stroke of the instrument to cause said pulley, lever and links to advance said front section thereby to graduate the length of the cut hair.

2. A clipper of the character described constructed in accordance with claim 1, wherein said lever is formed with an approximately radial slot and including a connector adjustably fixed within said slot by which one end of said first-mentioned link is connected with said lever, said connector being adjustable lengthwise of said slot to vary the extent of movement of said front section.

3. A clipper of the character described constructed in accordance with claim 1, wherein said lever is formed with an approximately radial slot and including a connector adjustably mounted in said slot by which one end of said last-mentioned link is connected with said lever, said connector being adjustable lengthwise of said slot to vary the extent of movement of said front section.

4. A clipper of the character described constructed in accordance with claim 1, wherein said pulley and said first-mentioned link are removable and wherein said lever is formed with a means for use in connecting one end of said cable directly to said lever so that tension on said cable will operate the lever to advance said front section during a cutting stroke of the instrument.

JOHN RUSSO.
